OR D 15,065

No. 15, 065

June 17, 1884

UNITED STATES PATENT OFFICE.

PAUL GROEBER, OF NEW YORK, N. Y.

DESIGN FOR WALL-PAPER.

SPECIFICATION forming part of Design No. 15,065, dated June 17, 1884.

Application filed April 11, 1884. Term of patent 3½ years.

To all whom it may concern:

Be it known that I, PAUL GROEBER, a citizen of the United States, residing in the city of New York, county and State of New York, 5 have invented and produced a new and original Design for a Wall or Ceiling Covering, which is especially intended as a wall-hanging, of which the following is a specification.

The drawing represents a front plan view of to the design.

The design is floral in its character, in the modern renaissance style. The treatment is semi-conventional, and consists of tastefully-grouped flowers *a* in full bloom, in combination with scrolls and foliation. Leaflets *f* on sprays and masses of seed-pods *e* are employed with good effect, while tendrils *d*, developing leaves *b*, and scrolls *g* gracefully entwine amidst the floral decorations, giving harmony to the

design. On the left of the design is placed a full-blown rose, *c*, with sprays of leaves, and at the upper right-hand part of the design is shown an ear of corn with the husks turned back, exposing the corn; and the design is further enriched with fantastic floral devices and beaded ornamentation. The ground of the design is filled in with fine perpendicular line work.

I claim—

The design herein shown and described, consisting of groups of flowers, in combination with scrolls, foliage, seed-pods, and stems, and with full-blown roses and ears of corn scattered about through the design.

PAUL GROEBER.
